(57) **CLAIM**

The ornamental design for a third brake LED light, as shown and described.

DESCRIPTION

FIG. 1 is a perspective view of a third brake LED light showing my new design;

FIG. 2 is another perspective view thereof;

FIG. 3 is a front elevation view thereof;

FIG. 4 is a back elevation view thereof;

FIG. 5 is a left side view thereof;

FIG. 6 is a right side view thereof; and,

FIG. 7 is a bottom plan view thereof.

A top plan view is omitted, which is a mirror image of the bottom plan view.

The broken lines in the drawing depict environmental subject matter only and form no part of the claimed design.
